UNITED STATES PATENT OFFICE.

WILLIS A. SCHLEIT, OF SYRACUSE, NEW YORK.

DRAFT-REGULATOR FOR HOT-WATER HEATERS.

1,174,525.

Specification of Letters Patent.

Patented Mar. 7, 1916.

Application filed October 1, 1912. Serial No. 723,343.

To all whom it may concern:

Be it known that I, WILLIS A. SCHLEIT, a citizen of the United States, of Syracuse, in the county of Onondaga, in the State of New York, have invented new and useful Improvements in Draft-Regulators for Hot-Water Heaters, of which the following, taken in connection with the accompanying drawings, is a full, clear, and exact description.

This invention relates to certain improvements in draft regulators for hot water heaters for any purpose where it is desired to maintain a substantial uniformity of temperature and incidentally to prevent the excessive use of fuel.

It is particularly useful in connection with hot water heating systems for incubators, brooders and the like, in which a close regulation of temperature is necessary.

The primary object is to utilize the temperature of the water leaving the heater for regulating directly a check damper and indirectly a draft damper controlling the combustion chamber.

Another object is to provide a construction having a minimum number of parts and adapted to be assembled with ease, through which any movement of the check damper beyond a predetermined point is positively and directly transferred to the draft damper controlling the combustion chamber, so that the regulation by the check damper shall be accompanied by a further and more sensitive regulation by the draft damper.

Other objects and uses will appear from the following description.

In the drawings Figure 1 is a front elevation of a heater and a part of a hot water circulating system connected thereto embodying the features of my invention. Fig. 2 is a cross section on line 2-2 Fig. 1. Fig. 3 is a cross section on line 3-3 Fig. 1. Fig. 4 is an elevation, partly in section, of the damper for the combustion chamber and its supporting member. Fig. 5 is a view, partly in section, of the regulating device, showing the manner in which it operates the check damper.

In order that my invention may be clearly understood, I have shown an upright boiler —1— as provided with a combustion chamber —2— and a water jacket —3— surrounding the combustion chamber and adapted to be connected to the water circu-

lating pipes —4— and —5— forming a part of a heating system. The water jacket —3— is closed at the top by a partition wall —6— having a central opening —7— therethrough leading from the combustion chamber —3— to a smoke chamber —8— formed by a hollow top section —9—. The section —9— is provided with an outlet —10— and a check port —11—, the outlet —10— adapted to be connected to a suitable chimney, not shown, while the check port —11— is provided with a suitable check damper —12— hinged at its upper edge at —13— to the section —9—. The top of the section —9—, which is preferably flat, is formed with a central opening —14— having a lid or closure —15— fitted therein and normally closed. The opening —7— in the upper end of the fire-box —2— is provided with a movable closure or draft damper —16— having a central aperture —18— through which a rod —19— and its surrounding sleeve —20— loosely extend. The rod —19— is threaded for a portion of its length on each end, and the sleeve is rigidly confined thereon by the washers —21— and the nuts —22—, the washers —21— serving to limit the movement of the disk —16—. The rod —19— extends upwardly through a plate —23— and has its end upset to prevent removal therefrom. The ends of the plate —23— extend at right angles to the body thereof and are provided with bearings —24— adapted to be removably positioned in the hook eyes —25— and —26— of a yoke —27—. The yoke —27— is pivoted by a pin —28— to a projection —29— extending downwardly from the top section —9— through an opening —30— in an arm —31— extending from the central part of the yoke —27—. The arm —31— is provided upon its end with a comparatively large flat plate —32— extending substantially parallel with and in proximity to the check damper —12— and of such weight that it will not quite balance the yoke —27— and the draft damper —16— supported thereby, so that the opening —7— is normally closed by the draft damper —16— but said damper will be raised therefrom when a slight pressure is exerted upon the plate —32—. The plate —32— is provided with two ears —33— and —34— projecting from the front face thereof and having openings therein to receive a rotating rod —36— having a circular disk —37—.

integral therewith and projecting to a greater distance from the face of the plate —32— than the ears —33— and —34— and constitutes an anti-friction bearing between the plate —32— and the damper —12—. When the check damper —12— is near closing point, it contacts with the disk —37— and its weight is transferred to the plate —32—, thus overbalancing the yoke —27— and the parts supported thereby and raises the draft damper —16— allowing free communication between the fire-pot —2— and the smoke chamber. By allowing the draft damper —16— to slide upon the sleeve —20— there is never any strain upon the valve itself as it will shift until the plate —32— contacts with the top section —9—.

It is apparent that the device so far explained will be readily operated by any means which raises and lowers the damper —12—, and I have shown the same as automatically operated by a regulator —38— in direct communication with the outgoing pipe —4— of the heater by means of a pipe —39— and a T joint —40—.

The regulator —38— is provided with a chamber —41— within which is a closed cylindrical corrugated bellows —42— formed of thin sheet metal, and filled with a volatile fluid as oil, highly sensitive to slight changes in the temperature of the water rising in the pipe —39—. Upon the upper side of the bellows —42— rests a member —43— extending upwardly through the wall of the regulator —38— and provided with a knife-edge bearing contacting with a plate —44— of a rocking member —45— pivotally mounted upon the regulator —38— by means of the pin —55— extending through the member —45— and mounted in the ears —46— and —47— projecting from the regulator —38—. The rocking member —45— is provided with an opening —48— through which extends a metal bar —49— having upon one end a ball —50— and connected at its other end to a projection —51— upon the damper —12— by means of a bar —52— and bolts —53— and —54—, the bar —48— resting directly upon the plate —44— and is held in contact therewith by a screw —59— extending downwardly through a threaded opening —60— in the rocking member —45—. The plate —23— is provided with upwardly extending projections —56— and —57— connected by a bolt —58— forming a handle for readily lifting the plate —23— from the hook eyes —25— and —26— of the yoke —27— and thereby removing the draft damper —16— and its supporting frame from the smoke chamber.

The operation is as follows: As the temperature of the water in the outgoing pipe of the heater rises, the volatile fluid in the bellows —42— expands causing the top of

the bellows to rise and forcing the member —43— upward against the plate —44— thereby rocking the member —45— upon its pivot —55— and raising the end of the bar —49— connected indirectly with the projection —51— such connection being made rigid by means of bar —52— and the nuts —53— and —54—. As the end of the bar —49— rises, it draws along with it the check damper —12— allowing the plate —32— to swing upward, whereby the draft damper is lowered to close the opening —7— and shut off the outlet from the combustion chamber, whereby the combustion therein is decreased, the temperature of the water in the outgoing pipe decreases, the volatile fluid contracts, the rocking member —45— rocks back, the check damper —12— tends to close, the plate —32— is forced downwardly raising the yoke —27—, the plate —23— supported thereby, and lifting the draft damper —16— from the opening —7— whereby the combustion in the fire pot is increased and the temperature of the water raised.

By means of the ball —50— the temperature of the water may be automatically regulated at different predetermined degrees, the weight of the ball according to its distance from the pivot —55— tending either to overcome the pressure caused by the expansion of the volatile fluid, or at least to partially counteract it.

What I claim is:

1. A heater having a check damper and a draft damper, means for operating the check damper, and means attached to a wall of the heater and in contact with the check damper for transferring movement from the check damper to the draft damper in reverse form.

2. A heater having a combustion chamber and a smoke chamber, a draft damper for the combustion chamber and a check damper for the smoke chamber, means within the smoke chamber and attached to a wall thereof for transferring movement from the check damper to the draft damper in reverse form, and means for operating the check damper.

3. A water heater having a check damper pivoted to a wall thereof, a draft damper for the combustion chamber slidably mounted upon an upright rod, means for supporting said rod comprising a yoke pivoted from a wall of the heater, an arm projecting from said yoke and contacting with the check damper, and means for operating the check damper.

4. A water heater having a check damper pivoted to a wall thereof, a draft damper for the combustion chamber slidably mounted upon an upright rod, a supporting member pivoted to a wall of the heater and having one end connected to said rod, the other

end adapted to contact with the check damper, and means for operating the check damper.

5. In a water heater, a check damper, a draft damper, a supporting member for said draft damper pivoted to a wall of the heater and having a lost motion connection with said draft damper, means for operating the check damper, said supporting member being operated by the movement of the check damper to open and close the draft damper.

6. A fluid heater having a draft damper, a stem upon which said damper is mounted, a transversely extending bar connected to said stem, a pivoted member having one end in the form of a yoke, the arms of said yoke supporting said bar upon opposite sides of its connection to said stem, and means causing said member to move about its pivot to open and close the draft damper.

7. A heater for a fluid circulating system comprising a combustion chamber and a smoke chamber, a draft damper separating said chambers, a check damper for the smoke chamber, a stem upon which said draft damper is mounted, a transverse bar operably connected to said stem, a pivotally supported member having one end in the form of a yoke, the arms of said yoke supporting said bar upon opposite sides of its connection to said stem, the opposite end of said member operated by the check damper to move said member about its pivot to open and close the draft damper, and means for operating the check damper in accordance with the temperature of fluid in the circulating system.

connection to said stem, the opposite end of said member operated by the check damper to move said member about its pivot to open and close the draft damper, and means for operating the check damper in accordance with the temperature of fluid in the circulating system.

8. A heater for a fluid circulating system comprising a combustion chamber and a smoke chamber, a draft damper separating said chambers, a check damper for the smoke chamber, a stem upon which said draft damper is mounted to slide back and forth within predetermined limits, a transverse bar operably connected to said stem, a pivotally supported member having one end in the form of a yoke, the arms of said yoke supporting said bar upon opposite sides of its connection to said stem, the opposite end of said member operated by the check damper to move said member about its pivot to open and close the draft damper, and means for operating the check damper in accordance with the temperature of fluid in the circulating system.

In witness whereof I have hereunto set my hand this 21st day of September 1912.

WILLIS A. SCHLEIT.
